UNITED STATES PATENT OFFICE.

BELLE CAMPBELL HARRISS, OF NEW ROCHELLE, NEW YORK.

HOSE-SUPPORTER.

1,373,239.

Specification of Letters Patent. Patented Mar. 29, 1921.

Application filed August 13, 1920. Serial No. 403,342.

To all whom it may concern:

Be it known that I, BELLE CAMPBELL HARRISS, a citizen of the United States, and a resident of New Rochelle, in the county of Westchester and State of New York, have invented a new and Improved Hose-Supporter, of which the following is a full, clear, and exact description.

The object of the invention is to provide a new and improved hose supporter more especially designed for holding up women's hose without danger of tearing the hose, at the same time insuring a proper fit of the hose particularly across the knee.

Another object is to hold the upper or welt portion of the hose circumferentially to the wearer's leg thus relieving the hose of strain on any particular point and thereby preventing injury to the hose.

Another object is to provide a hose supporter capable of yielding relatively to the hose thus enabling the wearer to freely exercise the body and limbs without tearing the hose.

Another object is to hold the wearer's corset down to produce the desired straight front effect.

Another object is to permit the wearer to readily change the hose without requiring removal of the hose supporter from the wearer's limb.

Another object is to provide a hose supporter free of metallic parts which are liable to rust and injure the hose.

With these and other objects in view, the invention consists of certain novel features of construction as hereinafter shown and described and then, specifically pointed out in the claims.

A practical embodiment of the invention is represented in the accompanying drawings forming a part of this specification, in which similar characters of reference indicate corresponding parts in all the views.

Figure 1 is a perspective view of the improved hose supporter as applied;

Fig. 2 is an enlarged perspective view of the improved hose supporter with part broken out; and

Fig. 3 is a cross section of the same on the line 33 of Fig. 2.

The hose supporter in its general construction comprises a tubular body 10 provided at its upper portion with a welt 11 and at its lower portion with a hem 12 containing an elastic band 13. The body 10

with its welt 11 and hem 12 is made of a flexible material, preferably hose material, and is knit the same as ordinary hose. The elastic band 13 is made of a piece of elastic 60 webbing, and in practice the hem 12 is provided with a vertical slit 14 through which the piece of webbing is inserted into the hem. The piece of webbing corresponds approximately in length to that of the annular 65 hem 12, and the abutting ends of the webbing are fastened together by stitches 15 which also close the slit 14 and also serve to fasten the piece of webbing in position in the hem 12.

In using the hose supporter, it is slipped in place after the hose has been drawn in position on the wearer's limb with the welt 11 uppermost and the hem 12 with the elastic band 13 lowermost, and the said hem and 75 band are located immediately above the knee. It is understood that the hose supporter on account of being knitted and having the elastic band 13 can readily stretch circumferentially when drawing it in place 80 over the upper portion of the hose and hence the hose supporter is under tension and securely holds the upper portion of the hose in position on the wearer's limb above the knee. After the hose supporter has been 85 drawn into position on the hose the usual fastening members 20 of supporting straps 21 are connected with the welt 11, the said straps depending from the wearer's corset 22 in the usual manner.

It will be noticed that as the hose supporter is firmly held in place on the hose at the wearer's leg above the knee, the supporting strap 21 on account of being attached to the welt 11 holds the corset 22 down thus 95 providing the desired straight front effect. It will also be noticed that by the arrangement described, the hose is supported without danger of tearing it as the hose is not subjected at any particular point to strain, 100 and it will further be noticed that the hose supporter, on account of being under tension and encircling the upper portion of the hose, securely holds the upper portion of the hose in place, at the same time providing 105 relative sliding movement between the upper portion of the hose and the hose supporter in case the wearer exercises the body and limbs.

The hose supporter body 10 with its welt 110 11 and hem 12 may be matched in color with that of the hose. By the use of the hose

supporter the hose may be made less in length by several inches thus saving considerable material and expense especially in high-priced silk hosiery.

5 As the hose supporter is free of metallic parts, which are liable to rust, no possible injury can be done on account of this.

Having thus described my invention, I claim as new and desire to secure by Letters

10 Patent:—

1. A hose supporter, comprising a tubular body of flexible material and adapted to encircle the upper portion of a wearer's hose above the wearer's knee, the said body having a welt at its upper end and having a hem at its lower end and an elastic band held in the said hem.

2. A hose supporter, comprising a tubular body of flexible material and adapted to encircle the upper portion of a wearer's hose above the wearer's knee, the said body having a welt at its upper end and having a hem at its lower end, an elastic band held in the said hem and having its ends abutting, and fastening means fastening the said elastic band ends together and to the hem.

3. A hose supporter, comprising a tubular body of flexible material and adapted to encircle the upper portion of a wearer's hose above the wearer's knee, the said body being under tension when worn to hold the upper portion of the hose in place on the wearer's limb; the lower end of the said body being provided with an annular hem and an elastic band held in the said hem.

35 4. A hose supporter, comprising a tubular

body of flexible material and adapted to encircle the upper portion of a wearer's hose above the wearer's knee, the said body being smaller in circumference than the wearer's limb above the knee and being adapted to stretch circumferentially to snugly hold the upper portion of the hose in place on the wearer's limb, the upper end of the said body having a welt adapted to be engaged by fastening devices of supporting straps depending from the wearer's corset, the said body being provided at its lower end with an annular hem and an elastic band held in the said hem.

5. A hose supporter, comprising a knit tubular body of hose material and adapted to encircle the upper portion of a hose above the wearer's knee, the upper portion of the said tubular body having means adapted to be engaged by fastening devices of supporting straps depending from the wearer's corset, and an elastic annular band held on the said body and under tension when in use to hold the upper portion of the hose firmly in position on the wearer's leg.

6. A hose supporter, comprising a knit tubular body of hose material and adapted to encircle the upper portion of a hose above the wearer's knee, the upper portion of the said body being reinforced, and an annular elastic member on the lower portion of the said body and under tension when in use to hold the upper portion of the hose firmly in position on the wearer's leg.

BELLE CAMPBELL HARRISS.
